Inventor
John L. Murphy

By Watson E. Coleman
Attorney

UNITED STATES PATENT OFFICE.

JOHN L. MURPHY, OF CANTON, ILLINOIS.

MORTUARY TABLE, SURGEON'S OPERATING TABLE, AND THE LIKE.

Application filed December 8, 1925. Serial No. 74,133.

To all whom it may concern:

Be it known that I, JOHN L. MURPHY, a citizen of the United States, residing at Canton, in the county of Fulton and State of Illinois, have invented certain new and useful Improvements in Mortuary Tables, Surgeons' Operating Tables, and the like, of which the following is a specification, reference being had to the accompanying drawings.

This invention relates to improvements in mortuary tables, surgeons' operating tables and the like and has for an important object thereof the provision of a table of this character which is provided with a grid upon which the body to be prepared for burial or operated upon may rest.

A further and more specific object of the invention is the construction of a table of this character in such a manner as to permit drainage from about the body of body fluids, excretions, bathing water and the like which otherwise tend to collect about the corpse and often render the corpse odoriferous.

A further object of the invention is to provide a device of this character which may be either superimposed upon the ordinary mortuary or surgeon's table or embodied in a table in the construction thereof, as is found desirable.

These and other objects I attain by the construction shown in the accompanying drawing, wherein for the purpose of illustration is shown a preferred embodiment of my invention and wherein:—

Figure 1 is a plan view of a rack for mortuary and surgeons' tables constructed in accordance with my invention;

Figure 2 is a side elevation partially in section of a table embodying a rack constructed in accordance with my invention;

Figure 3 is a detail perspective view showing the construction of the rack.

Referring now more particularly to the drawing, the grid comprises a body 10 and a head rest 11. The body 10 comprises transversely extending end and intermediate bars 12 and 12^a provided with supporting feet 13 having cushion tips adapted to rest upon a suitable base. The bars 12 and 12^a are each formed in two sections, the coacting faces of the sections being provided with aligned notches 14. These notches combine in the assembled relation of the sections to produce openings of slightly less diameter

than the diameter of longitudinally extending rods 15 which form the support for the body of the corpse. The sections of the rods are held in their assembled relation after the rods have been placed in applied position by rivets or similar securing elements, as indicated at 16 and these securing elements serve to bind the sections upon the rods so that shifting of the rods with relation to the bars is prevented.

Certain of the bars are extended beyond one of the end cross members 12, as indicated at 18, to provide the head rest 11 and the extremities of these extensions are connected by a further bar 19 similar to the bars 12. The grid thus formed may be enameled and while preferably constructed as above, may be constructed of heavy wire netting or the like where this is found desirable. The completed grid may be painted or enameled, as is found desirable.

Such a grid may be employed upon the ordinary mortuary table or may be embodied in a table such as shown in the drawings wherein the grid is supported from a pan 21, the bottom 22 of which slopes to a drain outlet 23 beneath which is arranged a collection receptacle 24.

Since the construction of the grid is obviously capable of a certain range of change and modification without materially departing from the spirit of the invention, I do not limit myself to the specific structure hereinbefore set forth except as hereinafter claimed.

I claim:—

1. A corpse supporting grid for mortuary or surgeons' tables comprising cross bars longitudinally split to provide two sections one of which is provided with supporting feet and longitudinally extending bars inserted between the sections of the cross bars and to which the sections of the cross bars are clamped, certain of said bars at the center of the grid thus provided being of greater length than the remaining bars and being connected at their ends by a further cross bar to provide a head rest.

2. A corpse supporting grid for mortuary or surgeons' tables comprising cross bars longitudinally split to provide two sections one of which is provided with supporting feet and longitudinally extending bars inserted between the sections of the cross bars and to which the sections of the cross bars

are clamped, certain of said bars at the center of the grid thus provided being of greater length than the remaining bars and being connected at their ends by a further cross bar to provide a head rest, the cross bar sections having coacting grooves for the passage of said longitudinally extending bars,

the combined size of said grooves being less than the size of the bars to thereby permit clamping of the longitudinally extending bars between such sections. 10

In testimony whereof I hereunto affix my signature.

JOHN L. MURPHY.
